UNITED STATES PATENT OFFICE.

GROSVENOR N. ALLEN, OF CHICAGO, ILLINOIS.

DESIGN FOR A SPOON.

SPECIFICATION forming part of Design No. 35,202, dated October 22, 1901.

Application filed August 30, 1901. Serial No. 73,875. Term of patent 14 years.

To all whom it may concern:

Be it known that I, GROSVENOR N. ALLEN, of Chicago, in the county of Cook, in the State of Illinois, have invented and produced a new and original Design for a Spoon, of which the following is a clear and exact description, reference being had to the accompanying drawings, forming a part thereof.

Figure 1 is a top plan view of the spoon complete. Fig. 2 is a side elevation. Fig. 3 is a cross-section on line 3 3, Fig. 2.

As shown in the drawings, the leading or material feature of my design consists in the bowl-body *a* and having substantially oval-shaped or elliptical sides *b* and terminating at one end in the rounded end *c*, its opposite end having rounded corners *d* and terminating in a handle *e*. The lower face of the bowl-body is slightly convex at the rear end,

as shown in Fig. 2, and the convexity increasing as it approaches the forward end, as shown in said Fig. 2, until it reaches a short distance from the forward end, when the convexity again decreases. The whole forms a unique unitary article of manufacture. The upper edge of the bowl is slightly curved, as shown in Fig. 1.

Having thus described my invention, what I claim, and desire to secure by Letters Patent, is

The design for a spoon substantially as herein described and shown.

In witness whereof I have hereunto set my hand this 26th day of August, 1901.

GROSVENOR N. ALLEN.
